SOUND-TRANSFERRING MEANS.

Original application filed November 4, 1921, Serial No. 512,946, and in Germany October 28, 1920.
Divided and this application filed May 24, 1924. Serial No. 715,768.

The present invention relates to means for transferring sound vibrations from one vibratory body to another and is a division of our copending application, Ser. No. 512,946, filed 5 November 4, 1921. The term "vibratory body", as used herein, is intended to designate generically any body capable of executing physical vibrations, whether the body is formed of liquid, gas or a solid, or combinations 10 of these. The said copending application is directed to the more general features of the new sound transferring means which we call the "dual chamber"; while the present divisional application is to be directed to a 15 special form of the dual chamber invention in which one of the individual compartments is the auditory canal.

We will now describe our invention with reference to the accompanying drawing, in 20 which the single figure shows the embodiment of the dual chamber principle where one individual compartment is formed by the auditory canal.

Referring more specifically to the drawing, 25 10 indicates a casing or shell carrying the vibratory diaphragm 11 with which it forms a compartment 12. This compartment 12 represents one of the individual compartments of the dual chamber and is provided with the 30 sound aperture or passage 13 leading therefrom. In the preferred embodiment of our invention, as shown, the casing or shell 10 is in the form of a more or less shallow or flat funnel, closed at the flared or wide end by 35 the diaphragm 11, and provided at the converged or narrow end with the sound passage or aperture 13. When the diaphragm 11 is set in vibration, sound vibrations are imparted to the fluid within the compartment 40 12, and pass out through the aperture or passage 13. We have shown as a means for exciting the diaphragm 11, an electromagnetic contrivance, of the conventional type, formed of the armature 14 and the coil and field- 45 pieces 15; but it will be understood, of course, that this contrivance is shown simply by way of example, and that the use of other suitable means for exciting the diaphragm is contemplated. In the particular embodiment shown 50 the electro-magnetic device and the diaphragm may be considered as forming what is known as the receiver of an ordinary present-day telephone.

When the casing 10 is placed up against the ear so that the aperture 13 is substantially 55 in alignment with the auditory canal 16, the compartment 12 forms with the auditory canal a dual chamber connected by the sound passage or aperture 13. This dual chamber behaves or functions in the same manner as 60 the form of dual chamber disclosed in our copending application, Ser. No. 512,946, where both compartments of the dual chamber are constructed mechanically as a part of the sound transferring unit. 65

In accordance with the present invention, the individual compartment 12 is made of such predetermined size or volume with relation to the size or volume of the auditory canal 16 as to effect a predetermined change 70 in the amplitude to force ratio of the sound vibrations passing from the diaphragm 11 to the organs of hearing. Where it is desired, for example, to increase the force and decrease the amplitude of the vibrations of the dia- 75 phragm 11 during transference to the organs of hearing, the chamber 12 would be made larger than the auditory canal 16. To further improve the efficiency of sound transference, it may be found desirable to tune 80 the dual chamber, consisting of the chamber 12, passage 13 and chamber 16, to the frequency of the sound vibrations being transferred. This tuning of the dual chamber may not, however, always be found necessary in 85 practicing the invention.

While in the embodiment shown we have illustrated and described the means for transferring sound vibrations from a vibratory diaphragm to the organs of hearing, a prob- 90 lem encountered in the ordinary present-day telephone, it is to be understood that the present invention is not limited to the transference of sound vibrations from a diaphragm to the ear. The invention is, for example, 95 equally applicable for the purpose of transferring sound vibrations from a vibratory body of air to the organs of hearing.

We claim:

1. Means for transferring sound vibrations 100 to the organs of hearing, comprising a chamber adapted to have the vibrations imparted thereto and having a sound passage leading therefrom, the chamber being designed to cooperate through the sound passage with the 105 auditory canal to form a dual chamber having

individual compartments of such predetermined size relative to each other as to effect a predetermined change in the amplitude to force ratio of the vibrations during transfer-
5 ence therethrough.

2. Means for transferring sound vibrations to the organs of hearing, comprising a chamber adapted to have the sound vibrations imparted thereto and having a sound passage
10 leading therefrom, the chamber being designed to cooperate through the sound passage with the auditory canal to form a dual chamber tuned as a whole to the desired frequency.
- 15 3. Means for transferring sound vibrations from a vibratory body to the human ear, comprising a chamber adapted to have sound vibrations imparted thereto by said vibratory body and tapering toward a sound passage
20 leading therefrom adapted to cooperate with the auditory canal to form a dual chamber tuned as a whole to the desired frequency.
- 25 4. Means for transferring sound vibrations from a vibratory diaphragm to the human ear, comprising a chamber having a portion of its wall formed by said diaphragm and adapted to have sound vibrations imparted thereto by said diaphragm and having a sound passage leading therefrom adapted to
30 cooperate with the auditory canal to form a dual chamber tuned to the frequency of the sound vibrations employed.

5. Means for transferring sound vibra-

tions from a vibratory body to the human ear, comprising a chamber adapted to have sound vibrations imparted thereto by said vibratory body and having a sound passage leading therefrom adapted to cooperate with the auditory canal to form a dual chamber having individual compartments of such predetermined size relative to each other as to transform the amplitude to force ratio of the vibrations received from the said vibratory body substantially to that ratio suitable for the ear drum before imparting them to the latter.

6. Means for transferring sound vibrations to the organs of hearing, comprising a chamber adapted to have the vibrations imparted thereto and having a sound passage leading therefrom, the chamber being designed to cooperate through the sound passage with the auditory canal to form a dual chamber having individual compartments of such predetermined size relative to each other as to effect a predetermined change in the amplitude to force ratio of the vibrations during transference therethrough, and the dual chamber being tuned as a whole to the frequency of the sound vibrations.

In testimony whereof we affix our signatures.
